United States Patent Office

Des. 203,416
Patented Jan. 4, 1966

203,416

JUG

Clayton J. Ammondson, 730 Russell Ave., Reidsville, N.C.

Filed Mar. 31, 1965, Ser. No. 84,527

Term of patent 14 years

(Cl. D58—5)

FIG. 1

FIG. 2

FIG. 3

FIG. 4

FIG. 1 is a side elevational view of a jug embodying my new design, with the side opposite being a mirror image of the side shown;

FIG. 2 is a right side elevational view of FIG. 1;

FIG. 3 is a top plan view of FIG. 1; and

FIG. 4 is an enlarged sectional view of the handle element taken along the line 4—4 of FIG. 1.

I claim:

The ornamental design for a jug, as shown and described.
